WEATHER STRIP

John S. Benson, Culver City, Calif.

Application December 2, 1940, Serial No. 368,204

5 Claims. (Cl. 20—67)

This invention relates to a sealing device and relates more particularly to an automatic weather strip. A general object of this invention is to provide a simple, practical and very effective weather strip means or sealing means for doors, windows, etc.

Exterior doors, windows, etc. are usually hung or supported to have some clearance with their frames, sills, etc. to prevent binding due to swelling, sagging and warping. In the case of poorly built structures and in instances of poor workmanship, this clearance is often excessive. The wind blows through such clearance spaces chilling the interior of the building and carrying in dust, snow, etc. and rain water often seeps under and around the windows and doors. Weather stripping is employed to reduce the leakage of wind, rain and snow but is not altogether satisfactory. Such weather stripping usually consists of a strip of rubber, fabric, or the like, secured to the door or window and intended to operate by contacting with the sill, frame, etc. The conventional forms of weather stripping soon lose their effectiveness and even when newly installed do not provide a full tight seal. Further, in the case of doors and windows which open inwardly the conventional weather stripping carries water, snow, dust, etc. into the house or building when the door or window is opened.

An important object of this invention is to provide a weather strip which provides a tight effective mechanically actuated seal which precludes the possibility of wind, dust, snow, water, etc. from entering the building or residence.

Another object of this invention is to provide a weather strip which is automatically operated to form a complete tight seal during the final portion of the closing movement of the door or window and which automatically retracts during the first portion of opening movement of the door or window. The novel weather strip of the present invention is entirely automatic in its operation, being operated when the door or window is closed and being retracted and freed from the frame or sill when the door or window is opened. The automatic operation of the weather strip provides for a tight complete seal between the door or window and its frame or sill and releases the sealing element of the strip from the frame or sill during the start of the opening movement of the door or window, thus relieving the sealing element of the wear which otherwise would result from the mechanically actuated sealing element rubbing on the sill or frame.

Another object of this invention is to provide

an automatic weather strip of the character referred to which may be readily applied to various forms of doors and windows and which does not interfere with rugs, floor irregularities, or the like.

Another object of this invention is to provide an automatic weather strip of the character referred to which may be formed and installed to compensate for a non-parallel relationship between the door or window and its sill or frame to provide a complete effective seal under such conditions.

A further object of this invention is to provide an automatic weather strip of the character mentioned which is very inexpensive and easy to install.

The various objects and features of my invention will be fully understood from the following detailed description of a typical preferred form and application of my invention, throughout which description reference is made to the accompanying drawings, in which:

Fig. 1 is a fragmentary perspective view of a typical door and building structure illustrating the novel weather strip of the invention in its operative condition. Fig. 2 is an enlarged fragmentary front elevation of the weather strip and the adjacent parts. Fig. 3 is an enlarged fragmentary vertical detailed sectional view taken as indicated by line 3—3 on Fig. 2. Fig. 4 is a view similar to Fig. 3 showing the weather strip in its retracted position. Fig. 5 is an enlarged fragmentary horizontal sectional view illustrating the manner in which the movable member seals with the cam. Fig. 6 is an enlarged fragmentary vertical detailed sectional view of the weather strip in the actuated position and Fig. 7 is a view similar to Fig. 6 with the weather strip in the retracted position.

The automatic weather strip of the present invention is suited for use in many situations and may be varied in proportions, design, etc. to adapt it for many classes of installations. In the following detailed description I will describe the typical form and application of the invention illustrated in the drawings, it being understood that the invention is not to be construed as limited or restricted to the specific details herein described.

In the drawings I have shown a typical door D hung or supported in a doorway defined by a suitable frame F. The invention is not concerned with the details of the door D or the frame F as these elements may be conventional. The particular frame F illustrated has a stop

strip or stop S against which the door D engages when in the closed position. It will be assumed that the door D is an inwardly opening door and that it closes outwardly against the stop S. A suitable latch or lock L is provided to releasably retain the door D in the closed position. The threshold is shown equipped with a suitable sill 10, it being understood that the invention is not to be construed as limited for use with a sill.

The weather strip of the present invention may be said to comprise, generally, a strip member 11 attached to the door D, a hinged or swingable member 12 carried by the member 11 and equipped with a sealing part 13, and means 14 for controlling or operating the swingable member 12.

The member 11 serves as a support or mounting for the swingable member 12 and assists in shedding or deflecting the wind, water, etc. The member 11 is intended to be secured to the door D or window along the edge which is to be sealed. As illustrated in the drawings the member 11 is an elongate element of substantially uniform shape or cross section throughout. The length of the member 11 approximates the width of the door D, the opposite ends of the member being adjacent the vertical edges of the door. The supporting member 11 is arranged along the lower edge portion of the door D and is preferably firmly fixed to the door. It is preferred to mount or arrange the member 11 some distance above the lower edge of the door D as illustrated in the drawings.

In the preferred form of the invention the member 11 is an integral or one-piece element of sheet metal or other generally rigid material. The member 11 is formed to have a flat generally vertical mounting or attaching part 14a, a downwardly and outwardly sloping portion 15 and a roll or curl 16 along the lower edge of the portion 15. It is to be understood that the part 14a, the portion 15 and the curl 16 may each extend throughout the length of the member 11. The part 14a is adapted to lie flat against the outer face of the door D and is provided with spaced slots or openings for receiving attaching screws 17 or the like. The portion 15 slopes outwardly and downwardly from the lower edge of the mounting part 14a. The roll or curl 16 curves downwardly and inwardly from the lower edge of the portion 15, then curls upwardly and rearwardly and then curves upwardly and forwardly. The roll or curl 16 is substantially cylindrical and is hollow or tubular. In accordance with the invention the edge 18 of the curl 16 is spaced from the under side of the sloping portion 15 providing the tubular or hollow curl with a mouth or entrance. In the particular construction illustrated the edge 18 faces outwardly and slightly upwardly. The inner or rear side of the curl 16 is spaced a substantial distance from the face of the door D and the member 11 is usually mounted to have the curl 16 spaced some distance above the lower edge of the door. It is to be understood that the member 11 is sufficiently strong and rigid to maintain its shape under all conditions for use.

The member 12 is the active or movable element of the device being carried by the member 11 to swing between a raised or retracted position and a lowered or active position where its sealing part 13 seals with the sill 10. The member 12 is an elongate strip of sheet metal of rather heavy gauge or other material of substantial

strength. In most installations the member 12 is of about the same length as the member 11. The main or major portion of the member 12 is straight and flat and the member is provided at its inner or upper edge with a roll or curl 19 which nests in the curl 16 of the member 11. The roll or curl 19 preferably extends throughout the length of the member 12 and is designed and proportioned to shiftably and swingably suspend the member 12 from the member 11 by turnably engaging in the roll 16. The curvature of the roll 19 is substantially cylindrical and the roll conforms generally to the exterior of the roll or curl 16. The curl 19 enters the mouth or entrance of the curl 16, that is, it passes between the edge 18 and the under side of the portion 15. An inturned lip 20 extends along the edge of the curl 19 and is adapted to cooperate with the edge 18 to limit movement or swinging of the member 12 and thus prevent displacement of the member from the member 11. The roll or curl 19 curves upwardly and forwardly from the member 12 and then curves downwardly and forwardly so that when the member 12 is lapped or nested in the curl 16 the member 12 has its upper part at the inner side of the member 11. The member 12 may be assembled on the member 11 by entering the curl 19 in one end of the curl 16 and then moving the members 11 and 12 with respect to one another in a longitudinal direction. In accordance with the invention the engagement of the curl 19 in the curl 16 permits bodily shifting of the member 12 with respect to the member 11 as well as swinging of the member 12. As best illustrated in Fig. 2 of the drawings the curls 16 and 19 are formed and related so that the member 12 may bodily shift at either or both of its ends in a generally vertical direction with respect to the member 11. The engaged or nested curls 16 and 19 constitute a loose or free hinge connection between the members 11 and 12.

It will be observed that the curls 16 and 19 are engaged one with the other in such a manner that fluid cannot pass or leak between the members. If desired a sealing element 9 of rubber or the like may be provided in the curl 16 to provide a positive seal between the members 11 and 12. The element 9 may be tubular and is engaged by the lip 20. Out-turned beads or flanges 8 may be provided on the opposite ends of the member 12. The flange 8 at the inner or hinge edge of the door D may seal directly with the frame or stop S. The flange 8 at the free or outer edge of the door cooperates with the cam means 14 to be later described. The flanges 8 prevent rain water, etc. from running from the ends of the member 12 and assure effective seals at the ends of the member 12. The flanges 8 are not essential in every case.

The lower edge of the swingable strip member 12 is prepared or shaped to carry the sealing part 13. In the preferred construction illustrated a loop or curl 21 is formed on the lower edge of the member 12. The curl 21 curves downwardly and rearwardly and then upwardly and forwardly. The hinge curl 19 and the lower edge curl 21 are preferably integral parts of the member 12. In some installations it may be desirable or necessary to bevel off or slope the end of the member 12 at the free or outer edge of the door D so that the member does not interfere with or strike the frame F when the door is opened and closed.

The sealing part 13 is carried by the swingable member 12 to seal with the sill 10, frame, floor,

or the like, as the case may be. The sealing part 13 may be formed of rubber, a rubber composition, synthetic rubber, fabric and rubber, or like material which is flexible and resilient and resistant to the elements. Where the member 12 is provided with the roll or curl 21 the sealing part 13 may be in the nature of a flexible tube of rubber, or the like, slid or sprung over the curl to enclose the same. The sealing part 13 is split longitudinally so that it may be readily arranged on the curl 21 and may be cemented or vulcanized to the curl. In most installations the sealing part 13 extends along substantially the entire length of the member 12. It will be observed that the sealing part 13 is carried by and backed up by the rigid curl 21 to be effective in sealing with the sill 10. In the application of the invention illustrated in the drawings the sealing part 13 serves to seal with the sloping surface 22 of the sill 10, it being understood that the part 13 may seal with any other surface below the door D.

The position of the member 11 and the width of the member 12 are such that the part 13 seals with the surface 22 when the member 12 is swung down to a slightly inclined position such as shown in Fig. 3. The clearance space C under the door D or between the door D and the sill 10 usually determines the location of the member 11. Where the clearance C is substantial the member 11 is attached to the door D at a low position while if the clearance C is small the member 11 is arranged at a higher point. The swinging member 12 may be of standard width to adapt the device for practically all installations or may be made in a range of different widths.

The means 14 for moving or actuating the member 12 between its retracted position and its sealing position is a spring and cam means embodying a spring or springs which normally urge the member to its raised position and embodying a cam for swinging the member to its lowered sealing position. The spring element or elements for urging the member 12 to the retracted position may be varied considerably. In the construction illustrated there are spaced blade springs or leaf springs 23 attached to the door D to act against the inner side of the member 12. There may be a spring 23 adjacent each end of the weather strip assembly. The springs 23 are provided with flat mounting parts 24 secured to the outer face of the door D by screws 25 or the like. The springs 23 project forwardly from the lower edges of the mounting parts 24 and engage against the inner side of the member 12 to exert an upward force or pressure on the member. The springs 23 serve to normally urge the member 12 to its fully raised position shown in Fig. 4 of the drawings where the stop lip 20 cooperates with the edge 18. The retracting springs 23 are yieldable to allow the member 12 to swing down to the sealing position shown in Fig. 3.

The spring element may further include retainers or guides 26 for acting on the curl 19. The guides 26 project from the upper edges of the mounting parts 24 to have their outer edges adjacent the sloping portion 15 of the member 11. As illustrated in the drawings the guides 26 bear down against the upper surface of the curl 19. The engagement of the guides 26 with the curl 19 serves to prevent rattling of the member 12 and undesirable upward shifting and tilting of the member 12 with respect to the member 11. The guides 26 are yieldable to allow the sealing part 13 to conform to the surface 22 in cases

where the lower edge of the door D, the sill 10 are not parallel or horizontal. The engagement of the sealing part 13 with the surface 22 in such cases may cause the member 12 to shift upwardly at one end or the other with respect to the member 11 and the guides 26 yield to permit such automatic adjustment of the member 12. The guides 26 serve to maintain the hinge curl 19 in cooperation with the stationary hinge curl 16.

The cam element of the means 14 is attached to a stationary part of the building structure and is engaged by the member 12 as the door D closes to cause the member 12 to swing down so that its sealing part 13 seals with the surface 22. In most installations the cam element is attached to the frame F, for example, it may be secured to the stop S. In the embodiment of the invention illustrated the cam element comprises a mounting flange 27 attached to the stop S. The flange 27 may flatly bear against the surface of the stop S and may have horizontal slots 28 for receiving attaching screws 29. The cam flange 27 is secured to the stop S adjacent the sill 10 and is positioned to cooperate with or to be engaged by the end portion of the member 12 which is at the free or outer edge of the door D. A cam rib or part 30 projects laterally from the flange 27 and presents a cam surface 31 which opposes the face of the door D. The cam face 31 slopes downwardly and outwardly at substantially the same angle as the angle assumed by the member 12 when the latter is fully actuated. The sealing element or part 13 terminates some distance from the end of the roll 21 leaving an end part of the roll exposed for cooperation with the cam face 31. The cam is located and constructed so that the roll 21 engages the upper part of the face 31 as the door D approaches its closed position. As the door D continues to close the engagement of the roll 21 with the cam face 31 causes the member 12 to swing downwardly and inwardly bringing the sealing part 13 into sealing engagement with the surface 22. The slots 28 allow the cam to be readily adjusted to provide the correct engagement of the roll 21 with the cam face 31. When the end of the member 12 has a flange 8, the flange seals with the cam face 31 to provide a seal at the end of the member 12. This is shown in Fig. 5. In the event the flange 8 is omitted the face of the member 12 directly seals with the cam face 31. In both instances the cam part 30 forms an overlapping sealing element for the end of the member 12.

It is believed that the operation of the mechanical or automatic weather strip provided by this invention will be readily understood from the foregoing detailed description. With the parts installed as described the weather strip is conditioned to provide a tight effective seal which prevents wind, rain, water, snow, etc. from blowing through the clearance space C. With the door D in the closed position the roll 21 bears against the cam face 31 to maintain the sealing part 13 in full firm sealing contact with the surface 22. The sealing part thus prevents the leakage or seepage of wind, water, etc. along the surface 22. The members 11 and 12 slope downwardly and outwardly to effectively shed or divert the wind, rain and snow and an effective seal is provided at each end of the member 12. When the door D is opened the member 12 of course moves away from the cam face 31 and the springs 23 automatically raise the member 12 to its retracted position. It will be observed that this retraction of the member 12 starts with

the initial opening movement of the door D so that the sealing part 13 is not dragged or scraped across the sill 10. The sealing part 13 is subjected to little or no wear. With the member 12 in the raised or retracted position the weather strip does not interfere with free movement of the door D and cannot engage irregularities of the floor or sill 10, rugs or the like. When the door D is closed the roll 21 contacts the cam face 31 just before the door reaches its closed position and the sealing part 13 is again automatically brought into engagement with the surface 22 to provide an effective mechanical seal. The parts of the weather strip are readily mounted and adjusted to assure the correct operation.

Having described only a typical preferred form and application of my invention, I do not wish to be limited or restricted to the specific details herein set forth, but wish to reserve to myself any variations or modifications that may appear to those skilled in the art or fall within the scope of the following claims.

Having described my invention, I claim:

1. A weather strip for sealing between a movable closure and a surface of a building structure comprising a supporting member to be secured to the closure to project from a face thereof, a curl on the member, a sealing member, a curl on the sealing member engaged with the first named curl to support the sealing member for swinging movement between a raised position and a sealing position in sealing engagement with said surface, a cam attachable to the building structure to be engaged by the sealing member to swing the same to said sealing position when the closure is moved to the closed position, and a single spring attachable to the closure for swinging the sealing member to the retracted position when the closure is opened and acting on the curl of the member to resist bodily shifting of the member.

2. A weather strip for sealing between a movable closure and a surface of a building structure comprising a supporting member to be secured to the closure to project from a face thereof, a curl on the member, a sealing member, a curl on the sealing member engaged with the first named curl to support the sealing member for swinging movement between a raised position and a sealing position in sealing engagement with said surface, said curls being loosely engaged to allow bodily tilting of said sealing member to conform to said surface, spring means yieldingly resisting said bodily tilting of the sealing member and urging the sealing member into uniform sealing engagement with said surface, and a cam attachable to the building structure to be engaged by the sealing member to swing the same to said sealing position when the closure is moved to the closed position.

3. A weather strip for sealing between a mov-

able closure and a surface of a building structure comprising a supporting member to be secured to the closure to project from a face thereof, a curl on the member, a sealing member, a curl on the sealing member loosely engaged with the first named curl to support the sealing member for swinging movement between a raised position and a sealing position in sealing engagement with said surface and to support the sealing member for bodily tilting so that it may conform to said surface, a cam attachable to the building structure to be engaged by the sealing member to swing the same to said sealing position when the closure is moved to the closed position, and springs attachable to the closure for acting on the sealing member to yieldingly urge the same to the retracted position and engaging the curl of the sealing member to yieldingly resist bodily tilting of the member and to urge the member into even sealing engagement with said surface.

4. A weather strip for sealing between a movable closure and a surface of a building structure comprising a supporting strip attachable to the closure to extend from the face thereof, an inturned curl on the lower edge of the supporting strip, a sealing strip member, an out-turned curl on the upper edge of the member loosely engaged with the first named curl to suspend the member for swinging movement and for bodily tilting, a sealing part on the lower edge of the member for sealing with said surface, a cam attachable to the building structure for swinging the member down to cause the sealing part to seal with said surface when the closure is moved to the closed position, spring means acting downwardly on each end portion of the second named curl to yieldingly resist bodily tilting of the member and to cause even engagement of the sealing part with said surface, and means for swinging the member upwardly when the closure is opened.

5. A weather strip for sealing between a movable closure and a surface of a building structure comprising a sealing strip member, means for supporting the member on the closure for swinging movement between a retracted position and a sealing position where it seals with said surface, said means comprising a strip element attachable to the closure, and nested hinge curls on the member and element, the outermost curl of said nested curls having an inturned edge part, a yielding sealing core in the innermost curl of said nested curls engaging with said edge part to seal between the curls, a cam attachable to the building structure to be engaged by said member to swing said member to its sealing position when the closure is moved to the closed position, and spring means for swinging said member to its retracted position when the closure is opened.

JOHN S. BENSON.
